MICROMETER CALIPER

Philip J. Darlington, Cambridge, Mass.; Rebecca T. M. Darlington, executrix of said Philip J. Darlington, deceased, assignor to Robert G. Morse, Marblehead, Mass.

Application August 27, 1931, Serial No. 559,708

Renewed January 6, 1937

10 Claims. (Cl. 33—148)

This invention relates to micrometer calipers and with regard to certain more specific features thereof, to high precision caliper gages.

The invention has for one of its objects to provide a sturdy and reliably operative gage, which shall be serviceable in various uses, quickly adjustable to accommodate different sizes of work over a substantial range, and adapted to indicate readings of extremely high precision. Other objects will be in part obvious and in part pointed out particularly in the description which follows of one preferred form of the invention. By the use of the gage hereinafter described there is an assured and maintained precision of diameter to plus or minus one-half of one ten-thousandth of an inch.

This extremely high precision in gaging is obtained by the combined action of a number of features of construction which reduce the errors of high multiplication gearing and substantially eliminate the personal factor of error. The dial indicator may be clearly read in ten-thousandths of an inch, and the effect of whipping of the indicator hand is neutralized. The invention permits the use of a low geared indicator with a dial reading in the above-mentioned high fractions, the amplification of movement between the caliper anvil and the indicator hand being effected in large part by leverage in the frame, which, coupled with a construction of anvil relationship and center-stop for the work causing each gaging operation to be ended by a controlled minus movement to zero, results in quickly obtaining accurate readings to the degree of precision stated.

The invention accordingly consists in the various features of construction, combinations of elements and arrangements of parts which will be exemplified by the following description and the drawing and the scope of the application of which will be indicated by the appended claims.

In the drawing:

Figure 1 is a view in perspective of the improved gage.

Figure 2 is a view in vertical cross-section of the gage shown in Figure 1.

Figure 3 is a top plan view of the gage shown in Figures 1 and 2 with parts broken away to show more clearly the clamping means for one of the anvils with the indicator removed and certain parts in section.

Figures 4, 5 and 6 are fragmentary views showing a modified form of contacting mechanism particularly adapted to the gaging of screw-threaded shafts or shanks.

Referring now more particularly to the drawing there is indicated at 10 a one piece main frame casting comprising side plates or walls 11 and 12 integral with a spacing web 13. The side walls of the frame are provided respectively with opposed slots 14 and 15 for the reception of parts of a quick adjustable contact element 16. The spacing web 13 is continued forwardly at its lower region to provide a boss 17 to which is secured a stop member 18 for purposes which will presently appear. Between the side walls 11 and 12 a lever 19 is pivoted at 20. This lever is of the bell-crank type having a lower substantially horizontal arm 21 and an upstanding arm 22. The lower arm at its free end carries the lower contact 23 of the gage. The upstanding arm 22 is provided at its free end with a cam plate 24 extending forwardly of the arm. The plate is provided with a cam face 25 which bears against a pin 26 of a lever arm 27, also pivoted between the side walls of the frame at 28. The lever arm 27 is normally urged rearwardly, contacting the pin 26 with the cam face 25, by means of the usual spring plunger 29 of a standard make of dial indicator represented at 30 as pivotally mounted between the frame walls on a pin 31.

The pivoted bell crank lever 19 carrying the lower caliper contact 23 is normally held against the stop 18 on the frame by a coiled retractile spring 32 connected to the lever arm 21 at 33 and connected at its upper end to a cross bar 34 attached to the upper part of the frame. This holds the lever arm 21 normally and yieldably in substantially a right angle position with respect to the forward vertical edge 35 of the frame.

A supplemental frame part 36 is formed of sheet metal curved to present opposed edges 37 and 38 to the exterior of the frame walls 11 and 12 at their rear edges where the supplemental frame is secured by screws or other fastening means 39. The upper region of the supplemental frame is shaped to provide spaced walls 40 and 41 between which an operating handle 42 is pivoted at 43. The supplemental frame, operating handle and rear portion of the main frame with connecting web 13, constitute a convenient hand grip for the instrument whereby the operating handle naturally falls into position for operation by the palm, and the lever 19 may be pivotally moved in opposition to the retractile spring 32. To effect this the upper arm 22 of the lever 19 has suitable angularity to constitute a cam face 44 against which there may be brought to bear a projecting angle member 45 attached to the 55

inner side of the handle 42, but normally slightly spaced from the arm by means of a leaf spring 45' acting against a stop pin 45".

The upper caliper contact element 16 is a quick 5 adjustable device comprising a flat anvil or contact member 46 secured to an adjustable arm 47 which has a spline 48 adapted to project between the spaced walls of the frame at the forward machined edge thereof. A bolt 49 has its shank 50 10 rotatively mounted in a section 51 of the arm 47. The flatted head 52 of the bolt is entered in the opposed slots 14 and 15 of the frame with some clearance for assembly purposes but without capacity for complete rotation of the bolt head. 15 The threaded shank of the bolt is entered into a threaded bushing 53 which in turn is enclosed by a split operating member 54 having an actuating finger piece 55. The bushing and operating member are associated to rotate in unison 20 by tightening a screw 56 bringing the split band of the operating member tightly around the bushing. The arm 47 is recessed at 57 to receive the operating member and bushing. As the actuating finger piece is moved, rotating the operating member and interiorly threaded bushing, the threaded shank 50 of bolt 49 is axially moved 25 due to its incapacity to rotate beyond narrow limits. This binds or loosens the arm 47 with respect to the frame accordingly as the finger piece is moved in one direction or the other. It 30 is intended that the device when in clamped position should have the finger piece moved to a home position against the arm 47 as shown in Figures 1, 2 and 3. To loosen the clamp the finger piece is rotated substantially 90 degrees, thereby rotating the interiorly threaded bushing and urging the bolt rearwardly. To vary the clamping pressure the screw 56 is let off slightly, allowing for relative rotation of the bushing 53 35 and the split operating member 54. After such rotation the screw is again tightened so that the parts move in unison.

The gage may if desired be applied to the work 45 as it is in production on a machine tool as in grinding it may be used right in front of the wheel while grinding is in progress. It will be noted that the frame and projecting anvils are 50 of slight thickness, and in line with preserving the advantages of this construction is the idea of having the finger piece 55 moved home against the arm 47 when the caliper member 16 is clamped to the frame.

A center-stop 60 is provided with a spring clip 55 attached to a body 62. The latter is adapted to bear against the forward machined edges of 60 the frame in the same manner as the arm 47 of caliper contact element 16. A lower projecting end 63 of the clip 61 is provided with a slight cam face 64 which engages a rear surface of the stop member 18. An upper projecting end 65 of the clip 61 has a slight cam face 66 which is engaged by a machined rear surface of the quick-adjustable upper caliper contact element 16. As the latter is locked in adjusted position the center-stop 65 with its projecting lug 67 is firmly held in its location. The described center-stop is typical of a plurality of pieces having bodies of various lengths which may be furnished as a part of the device or equipment. As the upper contact element holds the center-stop the latter serves to locate the position of the upper caliper contact. The proper length of center-stop body is selected with a view to the rough size of the work to be gaged.

When the center-stop has been inserted and 70 the upper contact clamped the instrument is in

condition for operation by the handle and hand grip. Pivotal movement of the handle by pressure reacts upon the lever arm 22 of lever 19 urging the arm 22 forwardly and dropping the lower contact 23 on arm 21. The lever arm 27 is 5 also moved forwardly in ratio.

The contacts or anvils 23 and 46 are slightly converged toward their outer ends to obviate the effects of lost motion or backlash in the mechanism as later herein described. The jaws are applied over a master of the size to which the work 10 is to be reduced and the dial indicator is set to zero in the usual way. Subsequently, as the gage is applied to the work all movements of the pivoted lower contact are transmitted to the dial 15 indicator through the compound lever mechanism comprising the lever 19, the cam 24, pin 26 and lever arm 27. A screw 70 in the split upper end of lever arm 27 offers opportunity for adjustment at this point and bears against the standard 20 spring plunger 29 of the dial indicator.

By the described arrangement of anvils, replaceable center-stops, leverage and dial indicator, any application of the gage to the work results in the last movement of all the mechanism being 25 in a minus direction controlled by the anvils as they contact the work and the gage is moved onto the work to bring the center-stop against the circumference. During this movement the slight inward divergence of the anvils allows the dial indicator plunger to react against its immediate lever, which in turn reacts against the elbow lever which is already in motion by its spring. The operation, therefore, is one of primarily overrunning zero on the dial and then allowing the 30 dial indicator to determine its own reading by the action of its spring plunger against a leverage system which is stopped in motion when the center-stop abuts the surface of the work. The application of movement by the levers employed is, 40 of course, present in this direction of movement, permitting a relatively large plunger movement for a very small closing-in movement of the anvils.

In the embodiment shown, the dial index finger 45 of the indicator has its movement amplified to three times normal movement by the compound leverage mechanism described. This magnifies any deviation from standard and results in gaging 50 of the highest precision.

The importance of the slightly outwardly converging anvils combined with the amplifying mechanism should be particularly noted. Although the convergence is so slight as not to be 55 distinguishable in the drawing, such as a thousandth of an inch or less, the motion of the lower anvil is amplified all the way to the tip of the indicator pointer in a series of stages. There is mechanical contact between each stage and the next under the pressure of one or more springs. There is friction at pivots and bearings. There 60 is momentum in the rapidly moving parts when the "opening grip" is squeezed to apply the gage to the work or to the reference standard. After such action all these moving parts are liable 65 to come to rest in slightly different positions with reference to each other, producing different readings on the dial with the same position of the lower anvil, or, in other words, producing inaccuracy of reading. When they come to rest, 70 the last controlling influence may have caused some of them to fly apart, or, on the other hand, to squeeze together, or some of them to go one way and some the other. Under such conditions the feature of the converging anvils plays its 75

important part. It provides a final control influence which is always uniform. The gentle and very slight movement of the lower anvil which takes place as the gage is pushed upon the work until stopped by the center stop provides opportunity for all the internal strains to ease themselves and for all the moving parts to resume normal positions with reference to each other.

In Figures 4, 5 and 6 there is shown a modified form of contact or anvil construction whereby the instrument may be adapted to the gaging of screw threaded shafts. The general construction of the operating mechanism may be the same as previously set forth. The center-stop member may be used or it may be eliminated, or a body may be used which has no lug. It is within the scope of the invention to use a center-stop having a construction corresponding to the upper and lower contact elements presently described. The lower arm 21 of lever 19 is modified as shown clearly in Figure 4 of the drawing, to have attached thereto at the forward end a yoke 80. The quick-adjustable upper caliper 16 is modified to provide a yoke 81 at its forward end. These yokes are adapted to receive arbors 82 on which are rotatively mounted rollers 83 and 84 with annular ribs or ridges 85 which enter the threads of the piece being gaged. The roller 83 has a spacing portion 86 and the roller 84 has at its opposite end a spacing portion 87 whereby the ribs of the different rollers are arranged in staggered relation so as to properly enter the threads of the work piece at diametrically opposed points.

I claim:

1. A caliper instrument comprising a frame having a slideway, a caliper member arranged in said slideway for movement into different positions of adjustment, an opposed caliper member pivoted in said frame and yieldingly held toward the first said caliper member, and a detachable center stop arranged in said frame intermediate the said caliper members and secured therein by adjusting the adjustable caliper member in the slideway toward the opposed caliper member and securing it in adjusted position and adapted for removal when the adjustable caliper is unsecured and slid in the opposite direction.

2. A caliper instrument comprising a frame having a handle portion and a vertically slotted front, a stop member at said front, a lower caliper member pivoted in said frame, a spring normally holding said lower caliper member against the lower side of said stop, an upper caliper member arranged in the slotted front of the frame for sliding adjustment therein, means for securing the upper caliper member in different positions of adjustment relative to said stop, an indicator on the frame, means for transmitting movement of said lower caliper to said indicator, and a detachable center stop arranged in said slotted front and having downwardly and upwardly projecting spring clip means adapted to engage respectively a rear face of said stop member and a rear face of the upper caliper member when the latter is adjusted downwardly.

3. Apparatus for caliperizing cylindrical work, comprising a frame, a lower caliper member pivotally mounted in said frame, an indicator on said frame, means for transmitting movement from said lower caliper to said indicator, an upper caliper member slidably vertically adjustable in the front of said frame, means for securing said upper caliper member in different positions of vertical adjustment, and a center stop detachably arranged, so as to be replaced by a center

stop of a different length, in the front of said frame below said upper caliper and having means engageable by the upper caliper member in its downwardly adjustable movement and releasable by movement of the upper caliper member in the opposite direction.

4. A caliper instrument comprising in combination, a frame having two spaced side walls connected by a continuous transverse web which bounds an opening through the frame, an indicator having a portion extending between the side walls at the top of the frame and supported therein, said indicator having a spring pressed plunger, an elbow lever pivotally mounted in the frame between the side walls, a second lever pivotally mounted in the frame between the side walls in position to be acted upon by an arm of said elbow lever and having a free end bearing against the indicator plunger, a spring normally urging said elbow lever in a direction away from said second lever, opposed guides on the inner sides of the frame walls at the front of the frame, a caliper member slidably arranged in the guides, means for quick-releasably securing said caliper member in different positions along the guides, and means for moving the elbow lever in opposition to its spring; said elbow lever having one end constituting a caliper element opposed to the first said caliper element.

5. A caliper instrument having a one piece body frame comprising a transverse web defining a substantially central opening and side walls providing a channel around said web, a pivoted elbow lever and amplifying gearing arranged in said channel, said elbow lever having a caliper member at one end and a spring controlling its normal position, an indicator at the top of the frame associated for transmission of movement with said amplifying gearing, a slideway in the frame at the front, a center stop at the front of the frame, a caliper member arranged for sliding adjustment in said slideway, means for securing the latter said caliper member in adjusted position against said center stop, and hand grip means located at the rear of the said body frame having an actuating member normally spring held out of engagement with said elbow lever but adapted to be advanced upon it to move the same about its pivot.

6. A caliper instrument comprising a frame, a caliper member arranged for sliding adjustment in the front of said frame and means for securing said caliper member in an adjusted position and unsecuring said member when desired, comprising a bolt having a head portion shaped to be slidable but non-rotatable in said frame, a shank portion arranged in the caliper member and a threaded portion extending into an opening therein, a bushing in said opening threaded onto the extended threaded portion of the shank and held against lengthwise movement thereon by opposed faces of the caliper member, and a member extending outside of said frame for rotating said bushing to lessen or increase the longitudinal distance between said head portion and said bushing to thereby clamp or unclamp the caliper member in relation to the frame.

7. In a caliper, a frame, an elbow lever pivoted thereon having at one end an anvil, another anvil diametrically opposed to the first said anvil and adapted to be secured in different adjusted positions on said frame, a center stop arranged circumferentially between said anvils, spring means urging the elbow lever toward a stop position, a

second lever pivoted on said frame adapted to be acted upon by the other end of the elbow lever, and a dial indicator of spring pressed plunger type mounted on said frame to present the plunger to the outer end of said second lever, the said anvils having a normal setting with their opposed faces converging toward their outer ends.

5 8. In a caliper, a frame, an elbow lever pivoted thereon having at one end an anvil, another anvil diametrically opposed to the first said anvil and adapted to be secured in different adjusted positions on said frame, a center stop arranged circumferentially between said anvils, spring means urging the elbow lever toward a stop position, a second lever pivoted on said frame adapted to be acted upon by the other end of the elbow lever, and a dial indicator of spring pressed plunger type mounted on said frame to present the plunger to the outer end of said second lever, the 10 said anvils having a normal setting with their opposed faces converging toward their outer ends and said center stop being removable for replacement by another of different size.

9. In a caliper, a frame, an elbow lever pivoted 25 thereon having at one end an anvil, another anvil diametrically opposed to the first said anvil and adapted to be secured in different adjusted positions on said frame, a center stop arranged circumferentially between said anvils, spring means urging the elbow lever toward a stop position, a second lever pivoted on said frame adapted to be 30 urged the elbow lever toward a stop position, a

acted upon by the other end of the elbow lever, and a dial indicator of spring pressed plunger type mounted on said frame to present the plunger to the outer end of said second lever, the said anvils having a normal setting with their 5 opposed faces converging toward their outer ends and said center stop being releasable for removal by movement of the adjustable anvil permitting its replacement by a center stop of different size.

10. In a caliper, a frame, an elbow lever pivoted 10 thereon having at one end an anvil, another anvil diametrically opposed to the first said anvil and adapted to be secured in different adjusted positions on said frame, a center stop arranged circumferentially between said anvils, spring means 15 urging the elbow lever toward a stop position, a second lever pivoted on said frame adapted to be acted upon by the other end of the elbow lever, a dial indicator of spring pressed plunger type mounted on said frame to present the plunger to 20 the outer end of said second lever, the said anvils having a normal setting with their opposed faces converging toward their outer ends, and a supplemental frame forming with a part of the main frame a hand grip and having a movable hand 25 operable part normally spring-pressed out of engagement with the elbow lever adapted to be moved to engage same and move it in opposition to its spring.

PHILIP J. DARLINGTON. 30
